US00D943222S

(12) **United States Design Patent** (10) **Patent No.:** **US D943,222 S**
(45) **Date of Patent:** **** Feb. 8, 2022**

(54) **PET FEEDER**

(71) Applicant: **SHENZHEN LEBEN TECHNOLOGY CO., LTD.**, Shenzhen (CN)

(72) Inventors: **Xun Xu**, Shenzhen (CN); **Zhiping Liu**, Shenzhen (CN)

(73) Assignee: **SHENZHEN LEBEN TECHNOLOGY CO., LTD.**, Shenzhen (CN)

(**) Term: **15 Years**

(21) Appl. No.: **29/749,930**

(22) Filed: **Sep. 10, 2020**

(51) LOC (13) Cl. **30-07**

(52) U.S. Cl. **USPC .....** **D30/122**

(58) **Field of Classification Search**

USPC ..... D30/121, 122, 129-133, 120; 119/61.5, 119/51.01, 61.56, 51.03, 59, 62, 63, 51.5, 119/57.8, 74, 61.54, 61.55, 53, 53.5, 75, 119/56.2, 51.02, 51.11, 51.12, 57.1, 52.1, 119/515; 312/204, 248/151, 188; 108/156, 153.1-157; 220/23.87, 630, 220/737, 743, 9.4, 495.01, 574, 212, 255, 220/23.83; 206/515; D7/586, 543, D7/550.1, 587, 505, 584, 545, 500, D7/553.1-553.8, 546, 555, 556, 504, 565, D7/562, 602, 605, 312, 313, 320, 307, D7/306, 309, 354, 311, 399, 397, 323, D7/332, 331, 347, 346, 322, 318, 317, D7/316, 619.1, 358; D9/429; 43/109; D22/122; 99/430, DIG. 15, 280, 285, 99/312; 222/209, 131, 363, 349, 517, 222/153.13, 401, 1, 146.5, 23, 54, 64, 51, 222/156, 399, 400.8; 219/438, 439, 441, 219/385, 386, 402, 407; 210/94, 184, 210/474, 477; D15/199; D12/86; D32/21, 23

(57) **CLAIM**

The ornamental design for a pet feeder, as shown and described.

DESCRIPTION

FIG. 1 is a perspective view of a pet feeder showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of portion 9 shown in FIG. 1. The broken lines in the drawings depict portions of the pet feeder that form no part of the claimed design.

1 Claim, 9 Drawing Sheets
